ELECTRIC CIRCUIT BREAKER

Charles Bresson, Villeurbanne, France, assignor
to Ateliers de Constructions Electriques de
Delle, Paris, France

Application August 2, 1933, Serial No. 683,351
In Germany August 1, 1932

2 Claims. (Cl. 200—150)

Electric circuit-breakers are known in which the arc is drawn out by displacement of the movable contact in a chamber filled with a liquid, the stationary contact being located in said liquid outside said chamber near an orifice in the latter, said orifice constituting a passage for the movable contact as well as a nozzle for the partial escape of the contents of the chamber subjected to pressure through the influence of the arc. In such a device, the movable contact at the end of the operation of opening is completely withdrawn from the chamber by issuing through a second orifice situated at the lower part of the chamber.

According to the present invention, the operation of this circuit-breaker is improved by increasing the height of the chamber which, in accordance with the invention, should be at least equal to $\frac{1}{3}$ of the maximum separation of the two contacts.

By the expression "height of the chamber" must be understood the mean distance separating the narrowest zones of the two orifices through which passes the movable contact.

The invention and its aims and objects will be readily understood from the following description taken in connection with the accompanying diagrammatic drawing of one illustrative embodiment of the invention.

In the drawing, the chamber containing the liquid, which may be insulating or conducting, is indicated by 1, the upper stationary contact by 2 and the lower movable contact shown in open position by 3. The chamber is terminated at top and bottom by nozzles 4 and 5 through which passes the movable contact shown in chain-dotted lines in closed position. The nozzle 5 is larger than the diameter of the contact 3 so as to enable the gases developed by the arc to escape through this nozzle during the displacement of the contact within the chamber 1. In certain exceptional cases the lateral walls of the chamber may be provided with orifices 6. The whole is disposed within a vessel 7 containing the liquid.

The operation of the circuit-breaker is as follows: on opening the circuit-breaker the contact 3 is lowered to the position in which it is shown in the drawing, and, as a consequence, the arc struck between 2 and 3 is drawn into the chamber in which it vaporizes a part of the contained liquid. This vaporization creates a rise in pres-

sure which provokes the expulsion of liquid and gases through the nozzles 3 or 4. On emerging from the nozzles these jets spread out, expand and are cooled. On the first passage of the current through zero a regenerated medium is thus created between the two contacts and as a result the striking voltage between the latter attains a high value and restriking of the arc is prevented. This effect even takes place when the pressure is only of the order of a few atmospheres.

It is evident that the invention is in no way limited to the vertical displacement of the movable contact and that the latter may move away from the stationary contact in any other direction whatsoever. On the other hand, the lower contact may be stationary and disposed below the chamber whilst the upper contact will consequently be movable.

Having now particularly described and ascertained the nature of my said invention and in what manner the same is to be performed, I declare that what I claim is:

1. In an electric circuit-breaker, an upper and a lower contact, said contacts being relatively movable and disposed in a liquid contained in a vessel, a chamber with upper and lower openings disposed within said vessel, the diameter of said openings being greater than that of said lower contact, said lower contact in closed position of 25 the circuit-breaker traversing said chamber through the two openings and leaving said chamber by the lower opening, the height of said chamber being at least equal to $\frac{1}{3}$ of the maximum separation of the two said contacts. 30

2. In an electric circuit-breaker, an upper and a lower contact, said contacts being relatively movable and disposed in a liquid contained in a vessel, a chamber with upper and lower openings disposed within said vessel, the diameter of said openings being greater than that of said lower contact, said openings constituting nozzles the interior walls of which are first convergent and then divergent, said lower contact in closed position of the circuit-breaker traversing said chamber through the two nozzles and leaving said chamber by the lower nozzle, the height of said chamber being at least equal to $\frac{1}{3}$ of the maximum separation of the two contacts. 45

CHARLES BRESSON.
